BLEACHER SEAT UNIT

Archer W. Richards, Chagrin Falls, Ohio

Application February 18, 1952, Serial No. 18,556

Term of patent 14 years

(Cl. D15—1)

To all whom it may concern:

Be it known that I, Archer W. Richards, a citizen of the United States, residing at the city of Chagrin Falls, county of Cuyahoga, State of Ohio, have invented a new, original, and ornamental Design for a Bleacher Seat Unit, of which the following is a specification, reference being had to the accompanying drawing forming a part thereof, in which—

The single figure is a perspective view of a bleacher seat unit, embodying my new design, the central portion being broken away for convenience of illustration.

I claim:

The ornamental design for a bleacher seat unit, substantially as shown.

ARCHER W. RICHARDS.
